J. H. Moore

United States Patent Office.

JOSEPH H. MOORE, OF CHICAGO, ILLINOIS.

Letters Patent No. 86,093, dated January 19, 1869.

IMPROVED RAIL FOR RAILWAYS.

The Schedule referred to in these Letters Patent and making part of the same.

To all whom it may concern:

Be it known that I, JOSEPH H. MOORE, of the city of Chicago, in the county of Cook, and State of Illinois, have invented certain new and useful Improvements in Rail for Railways; and I do hereby declare that the following is a full, clear, and exact description thereof, reference being had to the accompanying drawings, making a part of this specification, in which—

Figure 1 represents a side elevation;

Figure 2, a top or plan view; and

Figure 3, a cross-section through the chair.

Like letters refer to the same parts in all of the figures.

The nature and object of my invention consist in constructing rail for railways in parts, so that the parts can be made of different material; in making a detachable steel head or tread, and a strong soft-iron base or web; in connecting the steel head by concave neck, so that if it should be broken, it will not thereby become displaced; and in arranging the three principal parts, so that when a weight is placed or runs over them, the action of the weight will tend to make the sides press against the neck with increased force.

To enable others skilled in the art to make and use my invention, I will proceed to describe its construction and operation.

The head A is made of steel, and the top is curved in the usual manner, and it is made of the usual size.

The under side is made with straight lines running to the neck a. This neck a extends down about one inch, and has concave sides, with projections b fitting into them.

It will be obvious that grooves or other forms of fastenings can be used in place of the concave sides, but I prefer them made as shown.

The sides B are made of separate pieces of soft iron, and curved as shown, so that when placed on the track of a road, the appearance of the rail will not differ much from the appearance of the ordinary rail. At the upper edge, these side pieces are made to fit the shoulder of the head A, and near the upper edge, on the inside, are projections b fitting into the sides of the neck a.

In laying the rails, care should be taken, so that the joints of the sides shall not come opposite to each other, or in line with the joints of the head, but so that in all cases they will break joints, as shown.

Wherever a joint occurs in the side pieces, I place beneath the rail an iron cushion or chair, C, which is made of suitable plate-metal, and rolled, pressed, or otherwise formed into the shape shown, which forms

a support for the bottom of the side pieces B, and also a shoulder for the lower interior curve, so as to prevent them from being driven together while being spiked or fastened to the cross-ties. This object, however, can be accomplished by driving in billets or wedges of wood, or blocks of metal, and chairs dispensed with entirely.

The sides B are secured together by the rods, bolts, or spikes d, just below the neck a.

These bolts or ties d are a little smaller than the holes in the sides B, and hold by their heads or bent portions, so that when there is a weight upon the rail, these bolts or ties will act as fulcrum, and the web as a long arm of a lever, and thereby hold the neck of a rail as in a vise—the greater the weight upon the rail, the greater the grip on the sides of the neck.

If the tread of the rail should be broken into a number of pieces, no harm would come of it, as the pieces would be held in place, and if, by any possibility, any piece should come out, the train would not then be thrown from the track, as there would be enough of the rail left to guide the wheels. As the sides are made to "break joint," it would seldom, if ever, occur that all of the pieces would be broken at the same place.

So far as the clamping of the neck of a separate head is concerned, the head need not be made of steel; but to make my improved rail practically useful as a wearing rail, and as a device to prevent accidents, which occur by breakage of the rails as now made, I prefer steel heads.

The head A can be taken out at any time by withdrawing the spikes, and bringing the lower edges together, which releases their hold upon the neck of the head.

I do not claim making a rail in three sections, nor do I claim making the head or tread of steel, and the sides of iron.

Having thus fully described my invention, what I claim as new, and desire to secure by Letters Patent, is—

1. The combination and arrangement of the head A and sides B B with the loose bolt or tie d, so as to make the sides clamp the neck of the head, substantially as specified.

2. The combination and arrangement of the head A, provided with the neck a, the sides B B, provided with the curve or projections b, and rod or tie d, with the curved chair or cushion C, substantially as and for the purposes specified.

JOS. H. MOORE.
